[57] CLAIM

The ornamental design for a pull tool for unlocking a vehicle door without key, as shown and described.

DESCRIPTION

FIG. 1 is a perspective view of the first embodiment of the pull tool for unlocking a vehicle door without key, according to my new design;

FIG. 2 is a top plan view thereof;

FIG. 3 is a front elevational view thereof;

FIG. 4 is a bottom view thereof;

FIG. 5 is a rear elevational view thereof;

FIG. 6 is a left side elevational view thereof;

FIG. 7 is a right side elevational view thereof;

FIG. 8 is a perspective view of the second embodiment of the pull tool for unlocking a vehicle door without key, to be used by traffic constables according to my new design;

FIG. 9 is a top plan view thereof (symmetric bottom view);

FIG. 10 is a front elevational view thereof;

FIG. 11 is a bottom view thereof;

FIG. 12 is a rear elevational view thereof;

FIG. 13 is a left side elevational view thereof; and,

FIG. 14 is a right side elevational view thereof.
